AMUSEMENT DEVICE

Edward A. Rulfs, Los Angeles, Calif.

Application April 7, 1944, Serial No. 529,962

5 Claims. (Cl. 273—142)

This invention relates to amusement devices, and particularly to amusement devices of the chance-controlled type.

The primary object of the invention is to provide a device of this character which will be comparatively small to be carried in the pocket, the device embodying mechanism which will spin a coin within a supporting frame, means being provided for abruptly stopping the spinning of the coin to display one side of the coin.

Still another object of the invention is to provide a device of this character wherein it will be impossible for the operator to stop the coin with a predetermined side of the coin exposed to view.

With the foregoing and other objects in view, which will appear as the description proceeds, the invention resides in the combination and arrangement of parts and in the details of construction hereinafter described and claimed, it being understood that changes in the precise embodiment of the invention herein described, may be made within the scope of what is claimed, without departing from the spirit of the invention.

Referring to the drawing:

Figure 1 is a perspective view of the device.

Figure 2 is a plan view illustrating the device with the cover removed.

Figure 3 is a view of the device showing the cover removed, with the operating mechanism as forced inwardly to cause the spinning of the coin.

Figure 4 is a sectional view taken on line 4—4 of Figure 2.

Figure 5 is a sectional view taken on line 5—5 of Figure 2.

Figure 6 is a sectional view taken on line 6—6 of Figure 2.

Figure 7 is a transverse sectional view taken on line 7—7 of Figure 3.

Figure 8 is a transverse sectional view taken on line 8—8 of Figure 2.

Figure 9 is a perspective view of the operating member.

Referring to the drawing in detail, the device comprises a body portion indicated generally by the reference character 5, the body portion being in the form of a rectangular casing having a central opening of a diameter slightly greater than the diameter of a predetermined coin.

The sections of the body portion or casing, are held together by means of the rivets 6.

A circular frame indicated by the reference character 7 is mounted for spinning movement within the circular opening of the body portion,

this frame being provided with pintles 8 and 9, which are mounted within the bearing openings formed in the wall of the circular opening. As clearly shown by Figure 3 of the drawing, the pintles are provided with flattened ends, the flattened end of the pintle 8 being indicated by the reference character 10, while the flattened end of the pintle 9 is indicated by the reference character 11, the flattened ends 10 and 11, being disposed with their side faces at right angles with respect to each other, for purposes to be herein-after more fully described.

Positioned within the housing, and disposed adjacent to one end thereof, is a partitioning member 12, which has a curved inner edge conforming to the curvature of the central opening of the body portion. Right-angled flanges 13 are formed on the partitioning member 12, the free edges of the flanges contacting with the inner surface of the adjacent section of the body portion. The flanges 13 are spaced from the sides of the body portion, and provide compartments for coiled springs indicated at 14.

The operating mechanism comprises a substantially U-shaped member 15 which has offset portions 16 that provide stops to limit outward movement of the operating member when released by the operator. The operating member moves through slots formed in one end wall of the body portion, the offset portions 16 being enclosed within the housing, as shown by Figure 2 of the drawing. The inner ends of the operating member are extended laterally as at 17 and provide abutments for the inner ends of the coiled springs 14 which are placed under tension, between the ends 17 and one end wall of the body portion, with the result that normally, the operating member 15 is extended to the position shown by Figure 2 of the drawing, or to a position ready for operation.

Extended inwardly from one leg of the operating member, is a lug 18, which is adapted to contact the flattened portion 10 of the pintle 8 at a point beyond the pintle, to cause the frame and coin supported therein, to spin. The opposite leg of the operating member 15 is formed with an inwardly extended finger 19 which is so disposed that it will contact with the wide surface of the flattened portion 11 of the pintle 9, stopping spinning movement of the frame 7 and coin held therein. In using the device, the operating member 15 is normally in the position as shown by Figure 2. The device is now held between the index finger and the second finger of the hand of the operator, resting against one end of the body portion, the thumb of the hand resting against

the operating member. The operating member is now forced inwardly, whereupon the lug 18 contacts the flattened portion 10, spinning the frame and coin held therein, the coin being indicated generally by the reference character A. The operating member is immediately released to the end that the coiled springs expand, returning the operating member to its normal position. The inwardly extended finger 19 moves over the flattened portion 11 of the pintle 9, preventing further spinning movement of the frame 7 and the coin mounted therein, with the result that one face of the coin is exposed to view at the upper side of the device.

Various game rules may be followed in operating the device, without departing from the spirit of the invention.

What is claimed is:

1. A device of the character described, comprising a body portion having an opening formed therein, a frame mounted for spinning movement within the opening, said frame adapted to contain a coin, pintles extending from the frame and being mounted in openings of the frame, an operating member mounted within the body portion and adapted to be forced into engagement with one of said pintles, whereby said frame and coin are rotated, and means on the operating member adapted to engage one of said pintles, stopping rotation of said frame and exposing the sides of the coin to view in the plane of the sides of the body portion.

2. A device of the character described, comprising a body portion having an opening extending therethrough, a frame having pintles, mounted within the opening, blades on the pintles, said blades being disposed in planes at right angles with respect to each other, an operating member slidably mounted within the body portion, a lug on said operating member adapted to engage one of said blades, spinning said frame and coin held therein, and a lug extending from said operating member adapted to engage one of said blades, stopping spinning movement of the frame and coin, whereby the faces of said coin are temporarily held in planes with the sides of the body portion.

3. A device of the character described, comprising a body portion having a central opening, a frame in which a coin is held, mounted for spinning movement within the opening, pintles extending from the frame, a substantially U-shaped operating member extending into the body portion, means on said operating member adapted to engage one of said pintles, spinning the frame and coin held therein, when the operating member is moved in one direction, and means on the operating member adapted to engage the opposite pintle, stopping spinning movement of the frame upon reverse movement of said operating member, exposing the faces of the coin held within the frame, in the plane of the sides of the body portion.

4. A device of the character described, comprising a body portion having a central opening formed therein, a frame containing a coin, mounted for spinning movement within the opening of the body portion, pintles extending from the frame, said pintles having flattened ends, the flattened ends having their surfaces disposed in planes at right angles with respect to each other, an operating member slidably mounted within the body portion, said operating member adapted to engage one of the flattened surfaces of one of the pintles, rotating the frame when the operating member is forced inwardly, and a finger on said operating member adapted to engage the flattened surface of the opposite pintle, stopping rotation of said frame and exposing the faces of the coin held within the frame, in the plane with the sides of the body portion.

5. A device of the character described comprising a body portion having an opening formed therein, a frame in which a coin is held, mounted for pivotal spinning movement within the opening, an actuating member movable into the body portion and adapted to move in one direction spinning the frame, and said actuating member adapted to stop spinning movement of the frame and coin held therein exposing the sides of the coin to view in the plane of the sides of the body portion, upon movement of said actuating member in the opposite direction.

EDWARD A. RULFS.
